M. A. ANER.

AERIAL RAILWAY.

APPLICATION FILED APR. 23, 1919.

1,338,663.

Patented May 4, 1920.

UNITED STATES PATENT OFFICE.

MARTIN ABELLA ANER, OF LIVERPOOL, ENGLAND.

AERIAL RAILWAY.

1,338,663.

Specification of Letters Patent.

Patented May 4, 1920.

Application filed April 23, 1919. Serial No. 292,198.

To all whom it may concern:

Be it known that I, MARTIN ABELLA ANER, citizen of the Philippines, residing at Liverpool, in the county of Lancaster and King-
5 dom of England, have invented certain new and useful Improvements in Aerial Railways, of which the following is a specification.

In the Philippine group there are three
10 or four hundred islands many of them separated by only comparatively narrow water ways, and this application is especially designed for intercommunication between these islands, though it is also applicable
15 in other cases.

Referring to the drawings,

Figure 1 shows a view broken near the center, and at the ends of an installation between two islands:

20 Fig. 2 is a cross section of a terminal station post and two carriages:

Fig. 3 a cross section of a balloon support.

In these drawings, A is a lattice post carrying a lift B in the center; C booking office; D platform, D' supports grasping the cables with ball bearing joints D², thus keeping the carriage firmly held to the two cables; E a car. This car has a propeller F at each end and seats, etc., for passengers and guard. G is the upper main cable, and G' the lower main cable on which the carriage runs. R a wheel running on the lower main cable and forming with the latter a conductor to earth. J is a metallic hoop having a ball or other hinged bearing D³ around the lower cable and another similar bearing D⁴ around a cable K attached to a balloon L. This hoop J is preferably made of aluminium, M is the electric cable, 30 and N a trolley taking the charge from the electric cable. The two cables G' and G are firmly attached by wires O to strong abutments firmly anchored in the ground in the ordinary manner of suspension
35 bridges. P is a strong bracket on the post carrying the terminal bearings of the cables G', O'. It is partly cut away on the left-hand side and still more on the right hand side of Fig. 2 in order to show the mechanism, the cables running on a pulley Q and covered by another pulley R on the car.

The mode of action is as follows:—

On two islands not a very great distance apart are fixed two terminal posts and two
50 wires are carried across and firmly anchored

at each end. If the span is very long, balloons L with their rings J are fixed at intervals to carry the cables. The cars are placed at the terminal stations when the electricity is on and the trolley applied. 60 The cars pass along the wires between the two cables. I may in some instances, where the span is very long bring a shunt from the cable around the struts D, and form these as electro-magnets, so that they shall 65 have a strong pull on the steel cable holding it in place, but for short spans this is unnecessary, as there are sufficient balloons along the course to keep the cable suspended. The passengers are raised to the 70 terminal stations by the lifts B, and once every day or so a relief carriage goes along with stored hydrogen or helium, and supplies with fresh gas any balloon which appears to be weakening. In such instance 75 the gas is liberated from the balloon, the latter brought down to the car and the valve closed and the balloon filled with a fresh supply of gas. As the weight of the car is pretty considerable, and in long cables 80 or in long spans would give a strong tension on the cables, I form the cars with planes S, one on each side near the top like the planes of an aeroplane which can be put to any required angle and thus at the speed 85 used take off the entire weight, or such of the weight as desired, of the car from the cables.

In thus describing my invention, I do not bind myself absolutely to single spans, 90 as where there is a rock or a small island between two larger ones, I may place a post similar to A on the small island or rock and thus support the cables half way and indeed the railway can be made for miles 95 long if desired passing over several islands or over rugged country or the like by having posts at intervals.

I declare that what I claim is:—

1. An electric railway for crossing arms 100 of the sea or other difficult country, formed of two main cables for suspending the carriages one above and the other below, high posts carrying the cables, terminal anchorage abutments similar to those of other suspension bridges, and down which the return cable runs to earth, and trolley trains running on the main cable or cables, and trolleys for connecting the cars to the electric cable. 110

2. An electric railway formed of one or more main cables for suspending the carriages, high posts carrying the cables, terminal anchorage abutments similar to those of other suspension bridges, and trolley trains running on the main cable or cables, and trolleys connecting the cars to the electric cable, and balloons placed at intervals to take off the weight from the cables.
- 10 3. In an electric suspension railway, the combination of an aeroplane, one or more main cables for supporting the aeroplane, posts supporting the cables, open bearings on the said posts, arms from the aeroplane near each end projecting against the wire in the bearings and capable of passing through the bearings, an electric cable, a trolley from the car to the electric cable and an electric motor and propeller in the car to propel the carriage along the main cables.
- 15 4. In a two line electric suspension railway, the combination of supporting posts between the two lines, one or more main supporting cables for each line, cars running thereon, an electric cable for each line, trolleys from the car to the electric cables, and an electric motor and propeller in each car to propel the carriage along the main cables,
- 20 30 and adjustable planes attached to the car whereby the planes can take off the weight of the car from the cables when in motion.
5. In an electric suspension railway in which there are one or more main supporting cables and electric cable, and aeroplanes traveling on the main cables and supplied with electricity from the electric cable, the stations formed of a hollow post having a hoist therein placed between the two lines and a platform at the top.
- 40 6. In an aerial railway, a series of supporting posts, cables carried thereon and in long spans, one or more balloons between the posts, and framework surrounding and carrying all the cables (and the car when between them) between the posts.
- 45 7. In an electric suspension railway, the combination of two parallel supporting cables one over the other, a car and stout rods from the car at both ends holding on to both cables by antifriction devices in the vertical center line of the car.
- In witness whereof, I have hereunto signed my name this 3 day of April, 1919, in the presence of two subscribing witnesses. 55

MARTIN ABELLA ANER.
